UNITED STATES PATENT OFFICE.

WILLIAM VOSS, OF CHICAGO, ILLINOIS, ASSIGNOR TO THE FOX SOLID
PRESSED STEEL COMPANY, OF SAME PLACE.

TRUCK.

SPECIFICATION forming part of Letters Patent No. 431,089, dated July 1, 1890.

Application filed January 25, 1890. Serial No. 338,166. (No model.)

To all whom it may concern:

Be it known that I, WILLIAM VOSS, of the city of Chicago, county of Cook, and State of Illinois, have invented a new and useful Improvement in Trucks, of which the following is a full, true, and exact description, reference being had to the accompanying drawings.

This invention relates to an improvement in car-trucks in which springs are interposed between the axle and the truck with the advantage of relieving the truck from the strain and jar which usually affect it.

My invention will be readily understood from the accompanying drawings, in which—

15 Figure 1 represents a plan; Fig. 2, a lateral elevation; Fig. 3, an end elevation; Fig. 4, a transverse section through the end of the bolster; Fig. 5, a transverse section through the side frame and spring S, and Fig. 6 an inside 20 elevation of one of the spring-pockets.

The truck-frame may be, except as to the parts herein specifically described, of any usual and proper construction; but I prefer to make the same of the side pieces C, of 25 pressed flanged steel, and end pieces B, fitting thereto, and making, generally, a rectangular frame, as shown in Fig. 1.

The bolster, as shown, consists of two flanged steel channel-beams A A, provided 30 with center plate F, riveted thereto, and with side bearing-plates G G, likewise riveted or suitably fastened thereto. The ends of the beams A are bolted to the steel box K, as shown in Fig. 4, the box K and beams A A 35 being bolted to the side frame C and additionally resting upon the plate H, bolted through the lower flange of the side frame C. A similar plate may be bolted over the tops of the beams A A, as shown in Fig. 1. The

40 truck-frame does not rest in this construction directly upon the axle-journals, but is carried on equalizing-levers O O. The ends of the levers O O rest upon the ends of the axles L L through interposed springs N N, while 45 the side frames C C are hung upon equalizing-levers O O through links T T, the lower ends of which rest upon springs S S. The springs N N have their upper ends supported in the spring-caps P P and their lower ends 50 carried upon the axle-journal through suitable brasses, the ends of the axles being guided

in the pedestals in the usual way. The springs N N pass through cylindrical openings formed by the cylindrical depressions R R, and the internal semi-cylindrical covers R' R', making cylindrical openings, through which the springs pass. These depressions R R are preferably pressed in the side frames in the process of manufacture. In these side frames are likewise pressed the cup-shaped depressions D D, which, when combined with the inner members of the cups, as shown in Fig. 5, form a complete cup. The upper ends of the springs S S are supported in the spring-caps P P and the lower ends are carried in the 60 caps, to which are attached the links T T, carried upward and attached to the equalizing-levers O O, as at V. In this way it is obvious that the jar of the axle is transmitted through springs N N and springs S S before reaching 70 the side frames, truck, and bolster.

What I claim as my invention, and desire to secure by Letters Patent, is—

1. The combination, in a car-truck, of an equalizing-bar connected to the axles of the 75 truck, and springs between the bar and the truck-frame, the springs being supported in depressions in the frame, substantially as described.

2. The combination, in a car-truck, of two 80 axles, two springs connected with said axles, and an equalizing-lever attached to the frame of the truck by a spring-connection, substantially as described.

3. The combination, in a car-truck frame, 85 of the springs S S, bearing upon the truck-frame and interposed between said frame and the equalizing-lever O, the equalizing-lever O, and the springs N N, connected with the axle, substantially as described.

4. A truck side frame having pockets for the reception of the springs, consisting of lateral recesses pressed in the side frame, and semi-cylindrical covers secured to the frame, substantially as described.

In testimony whereof I have signed my name to this specification in the presence of two subscribing witnesses.

WM. VOSS.
